United States Patent Office

Des. 199,204
Patented Sept. 22, 1964

199,204

BOTTLE

Donald E. Dailey, Evansville, Ind., assignor to John H. Breck, Inc., Springfield, Mass., a corporation

Filed Oct. 11, 1962, Ser. No. 72,074

Term of patent 14 years

(Cl. D58—8)

I claim:

The ornamental design for a bottle as shown and described.
